LENS EDGE GRINDING MACHINE

Jorgen C. Andersen, Rochester, N. Y.

Application October 17, 1941, Serial No. 415,439

11 Claims. (Cl. 51—108)

This invention relates to lens edge grinding machines and more especially to machines for grinding the peripheral edge of large number of lenses to make them of uniform size and the principal object of this invention is to provide a novel machine in which one lens is efficiently mounted and centered at one station while another lens is accurately ground to size at another station in the cycle of operation of the machine.

A further object of this invention is to provide a lens edge grinding machine with a plurality of lens supporting spindles and cooperating driving means with which the lenses are rotated at a high speed for the lens centering operation and at a low speed for the edge grinding operation.

A still further object of this invention is to provide the machine with means for individually controlling the size of each lens relative to the center of the spindle on which it is supported.

Another object of this invention is to provide the machine with a novel indexing mechanism with which each of the plurality of lens supporting spindles is accurately located at the stations at which the various operations of the machine are performed.

Still another object of this invention is to provide the machine with an interlocking mechanism which prevents the release of any lens supporting spindle for movement from one station to another while a mounting and centering operation or a grinding operation takes place on one of the lens supporting spindles.

Another object of this invention is to provide the machine with self centering spindles and spindle bearings.

Another object of this invention is to provide a spindle carrying turret with novel driving means which, in its operation, automatically advances the turret for movement of the spindles from one station to another and then automatically drives the spindles for rotation of the lenses at a predetermined speed for cooperation with the grinding wheel.

Another object of this invention is to provide the driving mechanism of the machine with means whereby one of the spindles may be rotated at an increased rate of speed at one of the stations while the other spindles rotate at a uniform grinding speed at the other stations.

Another object of this invention is to provide the lens edge grinding machine with a novel drive operated by a single motor to have the various mechanisms of the machine operate to

efficiently perform their functions in cooperation with each other.

These and other objects secured by my present invention provide a lens edge grinding machine with multiple spindles in which each spindle has an individual size control with which the size of each lens is uniformly ground on all spindles of the turret, and in which the spindles are self adjusting and its bearing completely protected against intrusion of water, abrasives and dirt for substantially continuous operation controlled by an interlocking mechanism which makes it possible to use a practically inexperienced operator with but brief instructions for the operation of the machine.

The objects and attendant advantages of this invention will become more clearly apparent from the detailed description thereof which follows, reference being had to the accompanying drawings in which

Figure 1 is an end elevation of the machine.

Figure 2 is a rear elevation of the machine.

Figure 3 is a vertical sectional view of the machine taken on the line 3—3 of Figure 2.

Figure 4 is an enlarged front elevation of the upper portion of the machine.

Figure 5 is a horizontal sectional view of the machine taken substantially on the line 5, 5 in Figure 4.

Figure 6 is an enlarged sectional view of one of the clutches for the operation of a lens supporting spindle, the section being taken on the line 6—6 in Figure 5.

Figure 7 is a detail sectional view of one end of the lens supporting spindles, the section being taken on the line 7—7 in Figure 5.

Figure 8 is a vertical sectional view of the rear of the turret, the section being taken on the line 8—8 in Figure 5.

Figure 9 is a vertical sectional view of the index locking mechanism, the section being taken on the line 9—9 in Figure 5.

Figure 10 is a detail perspective view of the locking latch of the index locking mechanism.

Figures 11 to 15 inclusive show progressive positions of the indexing plate and its locking mechanism as it advances from the release of one of the locking pins to the locking position of the succeeding locking pin.

Figure 16 is a longitudinal sectional view of the micrometer size control, the section being taken on the line 16—16 in Figure 5.

Figure 17 is a top plan view of a modified form of the machine with a portion thereof broken away and illustrated in section.

As illustrated in the figures of the drawings, the machine is mounted on a base 1 which carries the bed 2 for the support of the transmission housing 3 at one end and the index housing 4 at the other end.

The turret housing 5 is located adjacent the transmission housing and is closed at the outer end by the end plate 6 and at the inner reduced end by the end plate 7. The latter concentrically supports the hub 8 of the spider 9 in the reduced end of the turret housing. The end of the hub 8 in turn is revolvably supported by the antifriction bearing 10 located in the fixed center bracket 11 of the transmission housing. A drive shaft 12 is mounted to freely rotate in the fixed center bracket 11 and the hub 8, and is revolvably supported at one end by the antifriction bearing 13 in the center bracket 11 and at the other end by the antifriction bearing 14 in the hub 8.

The end plate 6 at the outer end of the turret is supported by the turret shaft 15 which extends centrally thru this end plate into the turret where it is fixedly mounted in the bearing plate 16 carried by the spider 9.

The turret supporting shaft extends thru the index housing to the rear thereof where its reduced end is revolvably supported by the antifriction bearing 17. Clearance in the cap 18 of the index housing permits endwise movement of the reduced end of the turret shaft in the antifriction bearing and thus provides for expansion and contraction of the turret shaft at this end of the shaft without affecting its support of the turret and the driving mechanism associated therewith at the other end thereof.

Keyed to the turret shaft within the index housing 4 is the index plate 19 which carries four axially extending index pins 20, 20 that are radially spaced on the index plate and concentrically arranged thereon so as to be in axial alignment with the center of rotation of four lens supporting spindles 21, 21 in the turret housing 5.

Each lens supporting spindle is mounted to rotate in a spindle housing 22 which in turn is journaled in the end plate 6 of the turret and the bearing plate 16 of the spider 9 within the turret. Each of the spindle housings carries a sleeve gear 23 in mesh with the central drive gear 24 carried by the drive shaft 12. In this way rotation of the drive shaft by the worm or spiral gear 25 provides rotation of all four spindle housings with the spindles 21 projecting therefrom when the turret as a whole is locked against rotation. Transmission of the rotary movement of the sleeve gears to each of the spindle housings is thru a roller clutch made up of the clutch member 26 and the rollers 27, 27. This clutch member and the rollers are so formed and arranged that rotation of the sleeve gears, when rotated by the drive gear 24, causes the rollers 27 to be wedged between the wall of the sleeve gear and the clutch member as illustrated in Figure 6 and thus provides a driving connection between the sleeve gear and the clutch member and in turn the spindle which is keyed to the clutch member.

Rotation of the spindle housings and their spindles in this manner is at a predetermined low rate of speed which is most efficient for cooperation with the grinding wheel in grinding the edges of the lenses supported by the spindles as will hereinafter be described. However, before the lenses can be ground, they must be mounted and centered on the end of the spindles. Suitable

pitch is used for the attachment of one side of the lens to the end of the lens holders 21a carried by the spindle. The pitch at first is pliable on the lens holder 21a so that the lens may be adjusted and centered. This is done by spinning the spindle and the lens at a high rate of speed while the centering tool supported on the centering table 28 is held thereagainst until the lens runs true with the spindle.

- 10 To provide for the rotation of each spindle at a high rate of speed a tooth clutch member 29 is provided on the outer end of the hub of the clutch member 26. This tooth clutch member is adapted to cooperate with a corresponding tooth clutch member 30 carried by the drive shaft 31. The latter is movable endwise in the sleeve 32 which in turn is revolvably supported in the antifriction bearings 33, 33 in the transmission housing 3. The sleeve carries the pulley 34 for rotation thereof and the drive shaft which is splined thereto. A swinging yoke 35, which engages the drive shaft, is adapted to move the clutch member 30 into and out of engagement with the clutch member 29 for the rotation of each spindle when brought in alignment with the drive shaft 31 in the position in which the finished lens is taken off the spindle and a new one is attached and centered thereon.

The clutch connection provided between the clutch member 26 and its sleeve gear 23 permits the rotation of the spindle within the spindle housing at a higher rate of speed than the spindle housing because the higher rate of speed of the clutch member causes the clutch rollers 27 to release their wedging engagement with the sleeve gears and thus permit independent rotation at the higher speed without affecting the operation of the sleeve gears by the central drive gear 24.

As above pointed out, rotation of the spindle housings by means of the drive gear 24 and the sleeve gears 23, 23 takes place when the turret housing 5 is held locked against rotation. In this locked position one of the spindles is located near the operator at the front of the machine to permit the mounting and centering operation of a lens on that spindle, while another spindle is located at the rear of the machine to have the grinding wheel perform its grinding operation thereon. In this way while one lens is mounted and centered, another is ground and finished. As the turret has four spindles, one of the spindles is located intermediate the front and rear position at the top of the turret and carries an unfinished but centered lens ready for the grinding operation, while the other intermediately located spindle at the bottom of the turret carries a finished lens ready to be taken off therefrom.

The turret is held locked in each of its four positions by a latch mechanism provided in the index housing 4. This latch mechanism cooperates with the index plate 19 and the index pins 20, 20 carried thereby. The index plate is keyed to the turret shaft for rotation therewith, and the turret and the index pins 20 are arranged on the index plate in axial alignment with the spindles 21 in the turret. For the latch mechanism the index pins are made to project from the rear of the index plate for engagement with the locking latch 36. As illustrated in Figures 9 to 15 inclusive, this locking latch is mounted in the bottom of the index housing and is keyed to the rock shaft 37 so as to swing between the index pin extensions and the turret shaft 15 on the movement 75 of this rock shaft. The face of the latch ad-

jacent to the index plate 19 is cut out to provide in the upper portion the stop and guide pad 38 leading to the anvil stop 39 and locking channel 40 and to provide in the lower portion of the latch the gate 41.

The locking position of the locking mechanism is illustrated in Figure 9 in which an index pin extension is located in the locking channel 40 and rests against the anvil stop 39. In this position all other index pin extensions are free from the locking mechanism. However, when the locking latch is swung into the dotted line position illustrated in Figure 9, the index plate and with it the turret, is released so that rotation of the turret in the manner hereinafter described, causes the released index pin extension to move downward in front of the latch and thru the gate 41 behind the latch while the index pin extension at the top of the index plate moves in front of the top portion of the latch to limit return of the latch from its dotted line position by its engagement with the guide and stop pad 38 and have this index pin extension prevent full return of the locking latch until movement of the pin extension is arrested by the anvil stop 39. At this point the pin extension is free to enter the locking channel 40 into the locking position illustrated in Figure 9. For the purpose of releasing the index plate and the turret, the latch 36 is operated by the lever arm 42 keyed to the rock shaft 37 on the outside of the index housing at one end of the machine, and to return the latch into locking position this lever arm is provided with a counterweight 43 which operates to automatically swing the latch from its unlocked position back into locking position in the manner above described on the release of the lever arm by the operator.

Rotation of the turret on the release thereof by the latch mechanism in order to move the spindles with their lenses from one station to another is provided by the central drive gear 24 and the sleeve gears 23 which mesh therewith. To make this possible the lens spindles 21 are provided with the tapered bearing shoulders 44 which are drawn against the tapered bearings which surround them by means of the spring 45. The latter surrounds the spindle end and is interposed between the cap screw 46 and the shoulder 47 in the hub of the clutch member 26. The increased frictional contact provided in this manner between the spindle and its bearing causes a slight drag on the spindle which is overcome by the positive drive between the central drive gear and the sleeve gear as long as the turret is held stationary. However when the turret is released the draw on all of the spindles is sufficient to hold the spindles and with it the sleeve gears stationary so that the central drive gear, instead of rotating the sleeve gears, moves bodily in a planetary movement until the turret is held against further rotation at the next station. In the succeeding locked position the extra friction between the spindles and their bearing is again overcome by the driving effect of the sleeve gears and this causes the spindles to resume their rotation until the turret is released for movement of the spindles to the next station.

The mechanism so far described is driven by the motor 48 which is mounted on the swinging base 49. The driving pulley of this motor drives the pulley 50 on the transmission shaft 51 and a belt 54, which passes over a pair of spring tensioned pulleys 53, drives one of a pair of pulleys 56 from the pulley 52 of the transmission shaft

51. The pulleys 53 swing with the arm 55 and permit the raising and lowering of the pulleys 56 by means of the cam plate 58 by the handle 59. With the pulleys 56 in their lowermost position, 5 a belt 60 drives the pulley 61, which in turn rotates the spiral or worm gear 25 by means of a suitable worm (not shown) for operation of the turret and its spindles by means of the central drive gear 24. To stop operation of the turret and its spindles, as above described, the handle 59 is operated to move the cam plate 58 to raise the pulleys 56, thereby causing the belt 60 to disengage itself from driving engagement with its pulley 56. Transmission of power to the pulley 61 is thus interrupted to prevent further operation of the turret and its spindles thru the drive above described.

20 Rotation of the lens spindles in mounting and centering the lenses, which, as above described, is done at a speed higher than that provided by the turret drive, is secured by a pair of cone pulleys 62 and 63. Cone pulley 62 is carried by the transmission shaft 51 and drives cone pulley 63 by means of the belt 64. The shaft which carries cone pulley 63 has keyed thereto the pulley 65 and a belt 66 connects this pulley with the pulley 34 for rotation of the drive shaft 31 in the operation of a spindle 21 thru the tooth clutch members 29 and 30.

25 Operation of the yoke 35 for engagement of the tooth clutch members 29 and 30 is secured by the sliding rod 67 which is connected to the yoke 35 and is mounted to slide endwise in the bed of the machine with the free end of the rod projecting from the end of the machine. A bell crank 68 and link 69 connects the sliding rod with the treadle 70 so that depression of the treadle by the foot of the operator causes rotation of the spindle for centering purposes.

30 Spring 71 returns the treadle into inoperative position and disconnects the tooth clutch members after the centering operation is completed.

35 In order to prevent release of the turret for movement of the spindles from one station to another while one of the spindles is rotated by the tooth clutch members, the sliding rod 67 carries on the outside of the bed of the machine an interlocking block 72. This block is set so that movement of the sliding rod by the treadle to cause engagement of the tooth clutch members brings the interlocking block below the interlocking arm 73 which is attached to the rock shaft 37 and its lever arm 42. Release of the locking mechanism for rotation of the turret to advance the lens spindles can, therefore, not be effected until the centering operation of the lens is completed and the tooth clutch members are separated.

40 The grinding operation is performed by the grinding wheel 75 which is carried by the carriage 76. The carriage is clamped to and supported by the reciprocating and oscillating shaft 77 which is mounted in suitable bearings suspended from the bed of the machine at the rear so as to permit a swinging and endwise movement relative thereto. On the carriage 76 is supported the spindle housing 78 which is provided at one end with the combined journal and taper thrust bearing 79 and at the other end with a pair of antifriction bearings 80, 83. The spindle 81 which is revolvably supported in these bearings is free to slide endwise in the antifriction bearings and the spring 82 which surrounds the spindle at one end of the housing draws the tapered shoulder 83 of the spindle 81 into the

taper thrust bearing at the other end of the housing. The tapered shoulder of the spindle in engagement with the tapered thrust bearing steadies the spindle in its rotation in the spindle housing and causes the spindle to automatically keep itself centered in its bearing by the action of the spring 82 on the spindle. The antifriction bearing facing the inside of the spindle housing is a radial bearing, while the other antifriction bearing is a combined radial and thrust bearing to properly support the driving end of the spindle in the spindle housing. The spindle has the pulley 84 keyed thereto for the rotation thereof.

The grinding wheel in its attachment to the spindle is forced against the collar 85 which serves as a bearing guard that prevents intrusion of dirt, water and abrasives. In the end of the spindle housing and on the opposing face of the collar 85 are provided concentric ridges 86 and 87 respectively which are spaced by concentric grooves arranged in such a manner that the ridges of the collar engage into grooves in the end of the spindle housing and vice versa and thus provide a protective labyrinth between them that makes it difficult for foreign matter to pass therethru and enter the spindle bearing. The collar 85 is beveled on the side facing the grinding wheel and thus provides a circular deflecting channel between it and the wheel which causes water running off the wheel when at a standstill to be deflected from the end of the spindle housing.

The grinding wheel 75 is driven by the motor 48 thru the transmission shaft 51 and the pulley 88 carried thereby. A belt 89 drives a pair of pulleys 90 which are mounted to freely rotate and move endwise on the shaft 77. From these pulleys a belt 91 drives the pulley 84 and with it the spindle 81 and the grinding wheel 75 carried thereby.

As above pointed out, shaft 77 is also mounted to oscillate in its bearings and thus pivotally supports the carriage 76 to provide for the movement of the grinding wheel into and out of grinding contact with the lenses supported on the spindles of the turret.

The grinding wheel is manually brought into grinding contact with each lens and after the grinding operation is completed is again manually withdrawn from the lens to permit movement of the finished lens away from the grinding station and movement of an unfinished lens in its place. For this purpose the shaft 77 has keyed to the end thereof the handle 92 with which the shaft may be rocked to move the grinding wheel into and out of grinding contact with the lenses.

During the grinding operation it is of course necessary that the spindle, carrying the lens which is to be ground or is in process of being ground, rotate in an absolutely fixed position in order to have the grinding wheel perform its grinding operation accurately and uniformly on the lens supported thereon. For this purpose the turret is positively locked in each of its positions and to prevent the release of the locking mechanism while the grinding operation takes place, or prevent the movement of the grinding wheel toward the lens supporting spindles while the turret is released and moves its spindles from one station to another, an interlocking arm 93 moves with the handle 92 in its operation of the grinding wheel toward or away from a lens. This interlocking lever has a concentric locking edge 94

which moves in place under the interlocking pin 95 carried by the interlocking arm 73 of the locking mechanism which controls the rotation of the turret. The lever arm 42, by means of which the locking mechanism is operated for the release of the turret, is, therefore, locked against movement while the grinding wheel is moved to and from its grinding position as well as during its grinding operation. When the locking mechanism is released with the grinding wheel in its inoperative position, the interlocking pin 95 is moved in front of the interlocking arm 93 in order to prevent movement of the grinding wheel by the handle 92 until the interlocking pin is withdrawn from in front of the interlocking lever which takes place only when the locking mechanism has again locked the turret and holds its spindles at their proper stations.

Endwise movement of the grinding wheel during the grinding operation on the rotating lens edge is provided for by a reciprocating motion given to the shaft 77. For this purpose a suitable speed reduction mechanism 96 is driven from the transmission shaft 51 by the pulley 97 and the belt 98. This speed reducing mechanism operates a crank arm 99 and reciprocates the connecting arm 100. A lever link 101 is adjustably connected to the connecting arm and is fulcrumed on the swinging link 102. The upper end of the lever link carries a ball member which engages the ball socket 103 carried by the shaft 77. Oscillating movement of the lever link by means of the crank of the speed reducing mechanism thus causes the shaft to reciprocate in its bearings and move the grinding wheel back and forth during its grinding operation. The connection between the connecting arm 100 and the lever link 101 is adjustable to provide for an adjustment of the starting position of the grinding wheel in its reciprocating movement by the shaft 77. An increased or decreased reciprocation of the grinding wheel is provided by an adjustable connection between the crank arm 99 and the connecting arm 100.

45 The pressure of the grinding wheel on the lens during the grinding operation is determined by the counterweight 104 which is adjustably mounted on the arm 105. The latter projects from the bottom of the grinding wheel carriage 76 under the bed 2 of the machine as illustrated in Figure 3 and carries an upright 106 with an antifriction roller 107 projecting from the end thereof. With the grinding wheel in its inoperative position, the roller 107 engages the under side of the bottom 50 of the bed 2 of the machine and moves back and forth thereon to hold the grinding wheel carriage in the inoperative position while it is being reciprocated in the manner above described.

When the grinding wheel is moved into grinding contact with a lens, the arm 105 swings with it and overbalances the weight of the grinding wheel carriage and its grinding wheel in order to hold the grinding wheel against the lens edge at a predetermined pressure. This pressure may be increased or decreased by shifting the weight 104 either out or in on the arm 105. As the grinding wheel is moved into grinding contact the roller 107 is moved out of contact with the bed of the machine.

60 For the accurate size control of the lenses the index pins 20, 20 carried by the index plate 19 are provided with flat sides 20a, 20a which are ground thereon relative to the center and axis of their corresponding lens spindles 21 in the turret 5. These flat surfaces are radially arranged on the

index plate for cooperation with shoe 108 of the micrometer size control. This shoe is provided with the micrometer thread 109 which is threaded in the sleeve 110 but is held against rotation by the key member 111. The latter is mounted on the stationary supporting bracket 112 which forms part of the grinding wheel carriage and is located to one side of the grinding wheel. Adjustably clamped to the sleeve 110 by means of the adjusting nut 113 is the hand wheel 114 which is provided on its face with the dial 115. Rotation of the hand wheel thus causes the sleeve 110 to move the shoe in and out of the sleeve to provide a stop for the movement of the grinding wheel into grinding contact with the edge of the lens and permit gradual grinding of the lens edge on further adjustment of the shoe to the desired diameter as finally indicated by the pointer 116 on the dial 115. The dial 115 is held locked against the hand wheel for rotation therewith but may be released for adjustment relative to the pointer 116 for its starting position.

In this way the operation of the shoe by the handwheel accurately feeds the grinding wheel against the lens edge while the sliding contact of the shoe with the flat edge of the index pins accurately guides the grinding wheel back and forth over the lens edge.

In Figure 17 I have illustrated a modified form of the size control. In this modification the index pins carried by the index plate are replaced by flat bar members 117 which are mounted directly to the outside of the turret 5 and are circumferentially spaced and arranged axially parallel relative to the spindles. The outer surface of these bars is ground relative to the center and axis of their corresponding lens spindles in the turret for cooperation with the shoe 108 of the size control which in this case is mounted on the spindle housing of the grinding wheel carriage. This arrangement of the size control is desirable for heavier grinding on larger lenses.

For the purpose of balancing the grinding wheel on its spindle a compensating disc 118 is clamped to the outer face of the wheel. This disc is elongated and is provided with a slot 119 which permits it to be shifted transversely of the spindle as well as rotated thereon to provide for the necessary correction in balancing the grinding wheel on the end of the spindle.

I claim:

1. In a lens edge grinding machine having a plurality of rotating lens supporting spindles, the combination of guide means arranged parallel to and movable with each of said lens supporting spindles, size control means cooperating with each of said guide means and a grinding wheel guided for lateral and endwise movement relative to each of said spindles by said size guide means.

2. In a lens edge grinding machine the combination of a turret, a plurality of spindles rotatably mounted in said turret, a turret indexing plate axially spaced from said turret, a rotating grinding wheel, means for moving said grinding wheel axially parallel to and transversely toward and away from said spindles intermediate said turret and said indexing plate, a size control member arranged axially parallel to each of said spindles and movable therewith, and size control means movable with said grinding wheel and cooperating with each of said size control members for limiting the movement of said grinding wheel toward and away from the spindles and guiding the endwise movement of said grinding wheel relative to said spindles.

3. In a lens edge grinding machine the combination of a turret, a turret shaft for supporting one end of said turret, a spider supporting the other end of said turret, a plurality of spindle housings supported in said turret, a spindle revolvably mounted in each of said spindle housings, a gear carried by each of said spindle housings, a driving gear centrally of said spider for joint rotation of said gears, clutch means connecting said gears with said spindles for rotation thereof with the turret held stationary, and frictional contact between said spindles and said spindle housings to provide for planetary movement of said gears with said spindles and said turret by said driving gear.

4. In a lens edge grinding machine, the combination of an axially moving grinding wheel, a rotatable turret, a plurality of lens supporting spindles mounted in said turret, a guiding and indexing member arranged parallel to and cooperating with each of said spindles, indexing means cooperating with said indexing members for locating said turret in a plurality of stations adapted to have the lens supported by the spindles centered thereon at one of the stations and the lens edge ground to size at another station and cause said indexing members to guide said grinding wheel in its axial movement at the latter station.

5. In a lens edge grinding machine, the combination as set forth in claim 4 including means for rotating the spindles at a high grinding speed at the grinding station and common driving means for moving the turret from station to station and for rotating said spindles at a low centering speed at the centering station.

6. In a lens edge grinding machine the combination as set forth in claim 4 including a grinding wheel movable toward and away from and axially parallel to said lens supporting spindles and an adjustable sizing control member movable with said grinding wheel for movement into contact with and movement on said combined guiding and indexing members.

7. In a lens edge grinding machine, the combination of a rotatable turret, locking means for locking said turret into a plurality of predetermined positions, means for operating said locking means, a spindle mounted to rotate in said turret, spindle driving means, means for connecting said driving means with said spindle, and interlocking means operated by said connecting means for locking said operating means and prevent release of said locking means during rotation of said spindle.

8. In a lens edge grinding machine the combination of a turret carrying a plurality of spindles, means for releasing and locking said turret to cause rotation thereof to consecutively advance said spindles to predetermined stations, a grinding wheel, means for swinging said grinding wheel toward and away from one of said stations, an interlocking member carried by said locking and releasing means, and means cooperating with said grinding wheel for engagement of said interlocking member to prevent swinging of said grinding wheel on the movement of the release of said locking and releasing means.

9. In a lens edge grinding machine the combination of a rotatable turret carrying a plurality of rotating spindles, combined sizing and guiding members rotatable with said turret, a shaft mounted axially parallel to said turret and adapted to rock and move endwise relative thereto, a grinding wheel carriage supported by said shaft,

a grinding wheel mounted to rotate on said carriage, and a sizing control movable with said carriage for engagement of said combined sizing and guiding members to limit the rocking motion of said shaft and guide the endwise movement thereof and the corresponding movement of said grinding wheel.

10. In a lens edge grinding machine the combination of a base, a bed on top of said base, a transmission housing at one end of said bed, an index housing at the other end of said bed, a turret housing rotatably supported between said transmission and said indexing housing, a plurality of spindles mounted to rotate in said turret, a driving shaft for rotating said housing 15 jointly with said spindles, a second driving shaft

5 for individually rotating each of said spindles, a driving motor for the operation of both of said driving shafts, and means for transmitting movement from said motor at a high rate of speed to one of said driving shafts and at a low rate of speed to the other of said driving shafts.

11. In a lens edge grinding machine the combination as set forth in claim 10 including a grinding wheel carriage movable endwise and mounted to rock toward and away from said turret, a grinding wheel mounted to rotate on said carriage, means for transmitting movement from said motor to said grinding wheel, and means for translating movement from said motor into an oscillating motion for reciprocating said carriage.

JORG C. ANDERSEN.
